UNITED STATES PATENT OFFICE.

STEPHEN WOODWARD, OF FRANKLIN, NEW HAMPSHIRE, ASSIGNOR OF
ONE-HALF TO FREDERICK FLANDERS, OF SAME PLACE.

KNITTING-MACHINE.

SPECIFICATION forming part of Letters Patent No. 288,962, dated November 20, 1883.

Application filed November 3, 1882. (No model.)

To all whom it may concern:

Be it known that I, STEPHEN WOODWARD, of Franklin, in the county of Merrimac and State of New Hampshire, have invented a new 5 and Improved Knitting-Machine, of which the following is a full, clear, and exact description.

My improvements relate to ribbing attachments for knitting-machines, the object being to provide for working any desired number 10 of ribbing-needles, so that changes can be made from ribbed to plain work, or vice versa, without the necessity of changing the needle-operating cams or employing other usual devices for throwing a portion of the ribbing-needles 15 out of operative position. To that end I place the plate carrying the horizontal needles above the cam-plate and make use of jointed needles, which can be turned up, so that while all the needles are operated by the cam only those 20 turned down work the yarn, as hereinafter described and claimed.

Reference is to be had to the accompanying drawings, forming a part of this specification, in which similar letters of reference indicate 25 corresponding parts in all the figures.

Figure 1 is a vertical section of a knitting-machine provided with my improved attachment. Fig. 2 is a plan view of the needle-plate. Fig. 3 is an inverted plan view of the 30 needle-plate. Fig. 4 is a plan view of the cam-plate.

The needle-cylinder A and cam-ring B are of ordinary construction. C is the cam-plate of the ribbing attachment, and D the dial-plate. The cam-plate C is attached to the 35 lower end of a fixed shaft, a, that is secured at its upper end by a set-screw in an eye, d, on the end of the fixed arm e of the machine. The dial-plate D rests upon the dial cam-plate, and is attached to the ends of a yoke, b, which 40 is provided with a screw, e, entering the lower end of shaft a. The plate D is provided at its under side, as shown in Fig. 3, with slots for the shanks of the needles, and upon its upper side with a raised rim or flange, f, that is formed with slots for the hooked ends of the needles to rest in. The dial cam-plate, as shown in Fig. 4, is formed with a groove, which 45 is engaged by the lugs or projections of the needles, so that they shall be moved in and out when the plate is rotated. The hooked

ends of the needles l are separate pieces jointed to the main portion of the needles at i, so that the barbed ends can be turned upward, as illustrated in Fig. 1, and the ends of the jointed 55 portions are formed square, to rest upon the needle-plate when they are raised, so that they shall be retained in their raised position. The yoke b is rotated with the needle-cylinder by the contact of the projections k thereof with the arms of the yoke.

In the operation of the machine, when the jointed ends of the needles are turned downward, the work is ribbed by adding to the 60 number of stitches formed by the cylinder-needles the stitches formed by the dial-needles. In changing from plain to ribbed work, as 65 many dial-needles as may be required are turned down and set to work, as described, while the original number of cylinder-needles 70 are kept in use, both in plain and ribbed knitting. Thus the ribbed portion will contain as many more rows of stitches than the plain work does as there are dial-needles used. When it is desired to make the work partly ribbed 75 and partly plain, the jointed ends of the required number of needles l are to be turned upward, the loop on each being previously transferred to the cylinder-needles, and, the machine being then operated, all the needles 80 will still be worked in and out by the cam; but the yarn will be operated upon only by those having their hooked ends turned downward. To knit all plain, all the dial-needles l will be raised. In this manner the work 85 may be done all ribbed, partly plain and partly ribbed, or all plain without the necessity of changing the needle-operating cams.

Having thus described my invention, I claim as new and desire to secure by Letters Patent— 90

1. The jointed needles l, combined with the dial and dial cam-plates, substantially as shown and described, for use in the manner specified.
2. The combination, with the fixed dial cam-plate C, of the upper dial-plate, D, and jointed needles l, substantially as and for the 95 purpose set forth.

STEPHEN WOODWARD.
